UNITED STATES PATENT OFFICE.

GEORGE L. PITTMAN, OF BETHESDA, OHIO.

NUT-LOCK.

SPECIFICATION forming part of Letters Patent No. 709,357, dated September 16, 1902.

Application filed January 25, 1902. Serial No. 91,248. (No model.)

To all whom it may concern:

Be it known that I, GEORGE L. PITTMAN, a citizen of the United States, and a resident of Bethesda, in the county of Belmont and State of Ohio, have made a certain new and useful Invention in Nut-Locks; and I declare the following to be a full, clear, and exact description of the same, such as will enable others skilled in the art to which it appertains to make and use the invention, reference being had to the accompanying drawings, and to letters and figures of reference marked thereon, which form a part of this specification.

Figure 1 is a face view of my invention as applied. Fig. 2 is a perspective view of the pawl 2 in detail. Fig. 3 is a detail side elevation of the bolt. Fig. 4 is a fragmentary view showing the pawl as disengaged from the bolt.

The invention relates to nut-locks; and it consists in the novel construction and combination of parts, as hereinafter set forth.

In the accompanying drawings the letter *a* designates a threaded bolt, and *b* a nut thereon.

The bolt *a* is provided with one or more angular or V-form longitudinal grooves *c*, whereof the shoulders or bearing portions are radial, facing the lug *d* of the pawl 2, the other sides of the grooves sloping toward such lug at an angle of about forty-five degrees or less.

In each corner portion of the nut is provided a perforation. One of those perforations *f* receives a pin *g*, around the head *h* of which is coiled the middle portion of the spring *k*, whereof one arm *l* extends toward a corner of the nut and is provided with a terminal bend *m*, which engages a corner perforation *n*. Diagonally opposite this perforation *n* is a perforation *p*, in which is secured the pivot-pin *q*, whereby the pawl 2 is attached to the face of the nut.

The pawl 2 is made broad enough to engage one or more of the shouldered ends of the threads of the bolt in its groove. This pawl is provided upon one side of its pivot with a rear lug extension *s*, which extends toward the coil *w* of the spring and engages an upward terminal bend *v* of the arm *e* of the spring. The pawl is also provided upon the opposite side of its pivot usually with a handle extension *t* of its forward end and upon

the same side of the pivot as the pawl-tooth, such extension being long enough to reach beyond the perforation *z* in the other corner of the nut. The lug *d* of the pawl 2 is held in engagement with a groove of the bolt by means of the spring when the nut is turned home. When, however, it is designed to hold the pawl out of engagement with the nut, so that the latter can turn freely in either direction, a hold-off pin 3 is placed behind the extension *t* of the pawl, such pin engaging the perforation *z*.

Having described this invention, what I claim, and desire to secure by Letters Patent, is—

1. In a nut-lock, the combination with a grooved bolt, of the nut, the pawl pivoted to said nut, and having upon one side of its pivot a lug extension, and upon the opposite side of its pivot and upon the same side thereof as the pawl-tooth a handle extension, and the pressure-spring engaging said lug extension, substantially as specified. 65

2. In a nut-lock, the combination with a grooved bolt, of the nut, the pawl pivoted to said nut, and having upon one side of its pivot a lug extension, and upon the opposite side of its pivot and upon the same side thereof as the pawl-tooth a handle extension, a pressure-spring engaging said lug extension, and means adapted to engage said handle extension for maintaining the pawl in elevated position, substantially as specified. 70

3. A nut having four corner perforations, and in connection with one of them, a pin, and thereon a pawl, having a rear lug and a forward extension, in connection with a second perforation, a pin and thereon a coil-spring having one of its arms engaging the rear lug of said pawl and its other arm engaging the third perforation, the fourth perforation being adapted to receive a hold-off pin, substantially as specified. 80

In testimony whereof I affix my signature in presence of two witnesses.

GEORGE L. PITTMAN.
